CLAIM

The ornamental design for a handbag, as shown and described.

DESCRIPTION

FIG. 1 is an isometric view of a handbag, embodying our new design;

FIG. 2 is a front view of the handbag shown in FIG. 1; FIG. 3 is a rear view of the handbag shown in FIG. 1; FIG. 4 is a right-side view of the handbag shown in FIG. 1; FIG. 5 is a left side view of the handbag shown in FIG. 1; FIG. 6 is a top view of the handbag shown in FIG. 1; FIG. 7 is a bottom view of the handbag shown in FIG. 1; FIG. 8 is front perspective view of the handbag shown in FIG. 1 in an open position; and, FIG. 9 is an exploded view thereof.

The dash-dot-dash broken lines shown in FIG. 9 depict the order and arrangement of the separated parts in the exploded view and form no part of the claim. Any portions of the article depicted in broken lines form no part of the claimed design.

1 Claim, 8 Drawing Sheets(56)
